UNITED STATES PATENT OFFICE

2,250,872

OIL SEPARATING APPARATUS

Ralph G. Makely, West New Brighton, N. Y., assignee to The Superheater Company, New York, N. Y.

Application December 15, 1939, Serial No. 309,409

3 Claims. (Cl. 60—94)

My invention relates to improvements in separators and particularly those employed to separate oil from steam exhausted from engines, such as locomotive engines.

At least part of the steam exhausted from the engines of a locomotive is commonly utilized in exhaust steam injectors or feed water heaters of either the open or closed type. The lubrication of the locomotive engines results in entrainment of oil and grease by the exhaust steam and it is desirable to remove the oil, particularly where it may be carried to the locomotive boiler with the feed water as a result of being utilized in injectors or feed water heaters. Practically all exhaust steam from locomotive engines is superheated and it has been found that the separation of oil or grease in the presence of superheated steam is difficult. The present invention contemplates a partial desuperheating of the exhaust steam or more particularly the spraying of moisture into the steam in order to facilitate the separation of oil and grease therefrom.

In the drawing:

Fig. 1 is a diagrammatic elevational view of a locomotive equipped with a feed water heating system and an oil separating system embodying one form of the present invention.

Fig. 2 is a broken-away view of an enlarged scale of an oil separating system with some parts shown in section, a second and preferred form of the invention being illustrated in this figure.

Fig. 3 is a fragmentary elevational view of a locomotive feed water system embodying another modified arrangement.

Feed water taken from the locomotive tender through a suction line 10 is forced by an injector 11 to the locomotive boiler 12 through a delivery line 13. The injector is of the type which operates on exhaust steam when available in sufficient amount during operation of the locomotive and a conduit 14 connects the exhaust of engine 15 to the injector. Conduit 14 has an oil separator of any suitable type located therein, the separator being designated by the numeral 16. Whenever the injector 11 is operating, the water valve 20 (Fig. 2) is open admitting water to the chamber 21 to be forced into the boiler either by live steam or exhaust steam from the locomotive engine. With the arrangement illustrated in Fig. 2 the chamber 21 is connected by piping 22, 23, 24 to the exhaust steam conduit 14 at a point between the engine 15 and the oil separator 16. A suitable nozzle or the like 25 is employed so that cool water taken from the injector chamber 21 and sup-

plied through this piping is sprayed into the exhaust steam passing from the engines to the oil separator 16. Between the sections 23 and 24 of the piping is an injector 26 for drawing water from chamber 21 and forcing it into conduit 14, this injector receiving water from the section 23 and steam from the locomotive engines through a pipe 27. Interposed between the sections 22, 23 of the piping is a valve casing 30 containing a valve member 31. The valve is normally held closed by a spring 32 acting in opposition to steam pressure applied to a piston 33 through a conduit 34. This conduit is in communication with the cylinder 36 that is provided for the piston that opens the exhaust steam valve 37 of the injector. Whenever sufficient exhaust steam is available to operate the injector, the usual changeover mechanism such as that disclosed in Hard Patent Re. 19,229 dated July 3, 20 1934, causes steam to be admitted to cylinder 36 to subject the piston therein to steam pressure for opening the exhaust steam valve 37. Coincidentally, steam flows through conduit 34 to act on piston 33.

25 Whenever the injector 11 is operating, water valve 20 is open and accordingly cool water from the tender may be taken from chamber 21 and sprayed into the exhaust steam conduit 14 through the piping 22, 23, 24 provided the valve 30 31 is open. When sufficient exhaust steam is available for operating the injector the change-over mechanism causes steam to be admitted to the cylinder for piston 36, resulting in opening of the exhaust steam valve 37 of the injector. Inasmuch as the piping 34 is in communication with the chamber 36 this pressure also acts on piston 33 overcoming the force of spring 32 to open the valve 31 to permit water to pass from the injector through the piping 22, 23, 24 to be sprayed into the steam flowing from the engine 15 to the oil separator 16 on its way to the injector.

Instead of taking water from the chamber 21 of the injector the pipe 22 may be connected to the water delivery line 13 through which the injector forces water to the locomotive boiler, as illustrated in Fig. 1, and an injector is not required in piping 23, 24.

In the arrangement shown in Fig. 3 the water that is sprayed into the exhaust steam is taken by means of piping 40 from a steam and water separator or so-called "tangential drier" 41.

My theory is that the water sprayed into the exhaust steam combines with the oil therein so as to facilitate separation as by centrifugal ac-

tion in separator 16. In addition to aiding in the separation of oil from the exhaust steam, the addition of moisture to the steam by spraying water into it increases the fuel saving attained by the injector. Although the B. t. u. content of steam per pound is decreased, the specific volume is reduced to such an extent that more steam is condensed by the injector and the total B. t. u. value of exhaust steam entering the injector is increased, thereby increasing the fuel saving of the injector. Better performance may be obtained from the injector due to the possible increase in efficiency which results from an increased density of the injector jet.

Although the invention has been described in conjunction with the feed water system utilizing the exhaust steam injector, it will be apparent that it is also applicable to systems where the feed water is heated by exhaust steam in a heater of either the open or closed type because in all cases it is desirable to remove oil and grease from exhaust steam where there is a possibility that otherwise it may enter the boiler.

What I claim is:

1. In combination with an injector for forcing feed water into a boiler, a conduit connecting said injector to the exhaust of a steam engine, and an oil separator interposed in said conduit between said engine and said injector; a source of water connected to said injector; piping connecting the suction water side of said injector to said exhaust steam conduit at a point between said engine and said separator; and means for circulating water through said piping and spray-

ing it into the exhaust steam flowing therethrough before it enters said separator.

2. In combination with a boiler feed water injector supplied with exhaust steam through a conduit connecting it to a steam engine, a valve controlling admission of exhaust steam to said injector from said conduit; means for opening said valve when exhaust steam is available; and an oil separator interposed in said conduit between said engine and said injector; a source of water; piping connecting said water source to said exhaust steam conduit at a point between said engine and said separator for spraying water into the exhaust steam before it enters said separator; a normally closed valve in said piping; and means operative, when said exhaust steam valve is opened, to open said last-mentioned valve.

3. In combination with an injector for forcing feed water into a boiler, a conduit connecting said injector to the exhaust of a steam engine, a valve controlling admission of exhaust steam to said injector from said conduit, means for opening said valve when exhaust steam is available; and an oil separator interposed in said conduit between said engine and said injector; a source of water; piping connecting the water delivery side of said injector to said exhaust steam conduit at a point between said engine and said separator for spraying water into the exhaust steam before it enters said separator; a normally closed valve in said piping; and means operative, when said exhaust steam valve is opened, to open said last-mentioned valve.

RALPH G. MAKELY.
